7 Claims. (Cl. 100—48)

This invention relates to presses and particularly to presses for treatment of oleaginous materials either of animal or vegetable origin in order to remove their liquid content. More particularly the invention relates to a method of driving a press unit in order to increase the efficiency of the press, and reduce the amount of attention required to operate it.

In presses of the continuous screw type, it has been usual to arrange the pressing worms horizontally inside of a reticulate barrel structure including knife bars for preventing rotation of the material and causing it to build up pressure for the expressing of the liquid from the material under treatment. One example of such a structure is the disclosure of Anderson Patent No. 1,722,882. In such arrangements it is usual to have a horizontally mounted barrel with a vertical feed chute which discharges laterally into the inlet end of the barrel. The feed chute usually includes mechanical feeding mechanism such as a spiral, a continuous worm or the like. In the patent to Anderson No. 1,780,218, for example, liquid is expressed not only in the horizontal barrel, but preliminarily in the vertical chute, the result being to increase greatly the capacity of the press.

Regardless of the type of feeding mechanism employed and whether or not the feed chute includes expressing means, a power source must be employed in connection with the feeding means in the feed chute or hopper, and provisions must be made for variations in the density of the material or stoppage in the feed chute. Presses of the continuous type have the pressure within the barrel of the press controlled largely by regulating the choke at the outlet end of the barrel. This regulation is required whenever the material under treatment changes substantially in character or when the specific material being treated is changed as, for example, in pressing corn germs and then copra.

Extensive research has brought out the fact that if material is fed to the feed chute at a variable rate, depending upon its characteristics, the choke at the outlet end of the horizontal barrel may be fixed for any given material, and the feeding means be caused to impose a substantially constant discharge characteristic upon the press. Various means of accomplishing this result have been proposed. For example, it has been proposed to drive the shaft of the horizontal press by a motor, and then to connect this motor to the feeding means of the feed chute in order to actuate the two simultaneously. With

this arrangement there must be provision for slippage in the drive of the feeding means. This slippage has been provided for by use of an interposed friction clutch which will slip when the resistance to feed becomes too great, thus preventing damage to the mechanism.

This arrangement is satisfactory for the treatment of certain materials, but it offers the disadvantage that the friction means is subject to wear, and static and dynamic friction are not the same, hence such a clutch is difficult to maintain in satisfactory condition. The present invention is, therefore, directed to a solution of the problem overcoming the disadvantages of the arrangement pointed out above, while making it possible to drive the feeding means either from the source which drives the main press or to provide an individual power source for each. While the device is applicable to use with presses having separate drives for the press and the feeding means, the use of a single driving means is preferred for reasons of economy.

One object of the present invention is, therefore, to provide a driving means for the feed chute of a press, in which the rate of feed is varied automatically by changes in the character or condition of the material being fed.

Another object of the invention is to utilize impositive means in the form of an hydraulic torque transmitter of the kinetic reaction type for driving the feeding means of a press.

Other objects and advantages of the invention will appear from the following description when read in connection with the accompanying drawings, in which:

Figure 1 is a fragmentary side view partially in section of one form of press having the novel driving means of the present invention embodied therein; and

Fig. 2 is a fragmentary sectional view of a portion of the variable feeding means of a press having hydraulic torque transmitting means of the present invention connected to it, the feeding means being driven by a motor separate from that of the main press.

Referring first to Fig. 1, reference character 5 designates the base of a continuous screw press here shown as of the type disclosed in Anderson Patent No. 1,971,632. This base is hollow to form an oil collecting reservoir 6 to which oil is delivered from a horizontal barrel 7 and a vertical barrel 8. The horizontal barrel 7 is made up of a series of spaced barrel bars 9 with interposed knife bars 11, the whole being held together by longitudinal clamping members 12 and cross

members 13. Rotatably disposed within the barrel 7 is a main shaft 14 carrying a feed screw 15 and the usual interrupted screw flights 16, one of which is shown.

The inlet end of the barrel 7 is constructed as indicated in Patent No. 1,971,632, above described, with a feed chute 17 within which is rotatably mounted a feed worm 18, and interrupted screw flights 19 cooperating with the barrel bars 9a and knife bars 11a of the vertical barrel 8 to feed material and express a portion of its liquid content. The shaft 14 is driven at a predetermined speed by a motor 21 through interposed driving gears mounted in housing 22.

Associated with the feed chute 17 is the usual conditioning apparatus designated 23, from which material to be expressed is delivered into inlet 24 of feed chute 17. As here shown, the outlet end of the conditioner 23 contains a feed screw 25 to induce a continuous positive feed of material into the chute 17. This may be driven through suitable actuating means which includes a sprocket 26 and gearing 27, driven from motor 21 or other driving means, details of which are not important.

Feed screw 18 includes a shaft 28 which carries both the feed screw and the interrupted worm flights cooperating with the barrel 8. The shaft 28 may be driven at its upper end by a bevel gear 29 with cooperating bevel pinion 31 journaled in casing 32.

As shown in Fig. 2 of the drawings, the bevel pinion 31 is keyed to a shaft 33 journaled in casing 32 and having suitable antifriction bearings 34 and 35 carried by a casting 36, bolted to the casing as at 37. The shaft 33 carries hydraulic driving means of the impulsive or kinetic reaction type as distinguished from a positive drive, that is, the torque transmitted varies with the load. Consequently, the drive may slip when the load imposed upon it becomes too great, and there are no parts subjected to wear by such slipping. It comprises, as here shown, a closed casing made in two cup-like members or halves 38 and 39, bolted together as at 41 to form a chamber for hydraulic fluid. The member 38 of the casing includes a cylindrical bearing supporting housing 42 having a driving sprocket 43 keyed to it at 44. Roller bearings 45 and 46 are interposed between the cylindrical portion 42 and the shaft 33, while means, such as washers 47, 48, associated with the bearings 45 and 35, respectively, prevent escape of lubricant from these bearings, or the escape of hydraulic fluid from the casing 38, 39.

The casing contains hydraulic fluid such as oil for imparting movement to the shaft 33. For this purpose the half 39 of the casing carries a series of spaced radial vanes 49. Keyed to the shaft 33 as at 51 is a runner 52 carrying a series of radial vanes 53 of a construction similar to the vanes 49 on the element 39. The runner 52 includes a hub 54 passing through an opening 55 in the casing half 39 and sealed against escape of hydraulic fluid by a washer 56. The end of shaft 33 is threaded at 57 to receive runner adjusting means comprising a nut 58, clamping sleeve 59, and a lock nut 61. The bearing 46, disposed adjacent the runner 52, is held in position by a nut 62 threaded onto the shaft 33.

The operation of the driving means in a press arranged as illustrated in Fig. 1, is as follows: The sprocket 43 is operatively connected to motor 21 and this driving connection includes a chain indicated diagrammatically at 63, driven

from a sprocket 64 associated with the gearing in housing 22. As the sprocket 43 is driven, the casing containing the vanes 49 is caused to rotate, thus giving rotary movement to the oil or other fluid contained in the casing. This movement is transmitted by vanes 49 to the vanes 53 of runner 52, driving it and, in turn, driving the shaft 33. Bevel pinion 31 and bevel gear 29 drive the shaft 28 of the feeding means in feed chute 17. Whenever the load imposed upon shaft 28 by the material being fed increases, the speed of drive of runner 52 is reduced, and whenever resistance to drive decreases, the speed of runner 52 increases. In this way, although sprocket 43 is driven at a constant rate, the drive of shaft 28 varies in accordance with the load imposed upon it by the material being fed to the press. The speed of the runner 52 will, of course, always be somewhat less than that of the vanes 49.

It is possible, by varying the position of adjusting nut 58 to vary the clearance between the vanes 49 and vanes 53, to vary the driving effect. Accordingly, the nut 58 is moved to the left to increase the spacing between the vanes 53 and vanes 49, and to reduce the driving effect and, conversely, the runner is moved to the right to decrease the vane spacing and to increase the driving effect. Obviously the effect is to vary the maximum torque which may be transmitted, and thus vary the range of the automatic torque adjustment which occurs in response to the resistance offered by the material being fed. Suitable experimentation will determine the proper relation for the treatment of any given material. Once the adjustment has been made, the motor 21 which will normally be arranged to drive the horizontal press at a substantially constant rate, will drive the feeding means through the hydraulic drive and cause it to deliver material at a suitably coordinating rate, that is, the press barrels 7 and 8 will be caused to operate harmoniously once the choke associated with the horizontal barrel 7 has been adjusted. In this way, a single motor affords suitably coordinated action of the main and feeding presses without the constant attention of an operator. Likewise, a relatively simple driving means free from frictional wearing parts will be caused to vary the drive of the feeding means in accordance with the conditions imposed by the material to be expressed.

If, for any reason, solid material, sufficient to lock the vertical shaft, should be fed into the feed chute 17, slippage between the parts of the hydraulic torque transmitter will increase and interrupt the drive without damage to parts of the machine. The hydraulic torque transmitter has another advantage, namely, the conditions under which it takes up and releases its drive are uniform, that is, it is not subject to the difference between static and dynamic friction. Consequently, it operates effectively and uniformly regardless of the material being fed or the load imposed upon it.

While the preferred driving arrangement is for reasons of economy that of Fig. 1 (only one motor is required), it is entirely feasible to utilize a separate motor drive for the feeding means. Such an arrangement is shown in Fig. 2. With this arrangement the main press will be driven as indicated in Fig. 1 but a separate motor 65 will drive the sprocket 43 through chain 66 as shown, or by suitable equivalent means. The main motor will as usual be arranged to drive the main press at substantially constant speed. The

motor 65 will drive the sprocket 43 at a rate such as to vary the rate of feed of material in accordance with its characteristics or conditions. The details of operation will be carried out as set forth in connection with the arrangement of Fig. 1.

In the present description, the hydraulic driving means has been shown as applied to a particular type of continuous press, but it is to be understood that the use is not limited to the particular press arrangement illustrated, but may be applied to any continuous press employing a continuous feeding means. Consequently, the claims are to be construed broadly and without limitation to the particular type of press or the particular driving arrangements shown.

What is claimed is:

1. In combination, a press of the continuous type for expressing liquid from materials containing the same; continuous feeding means for the press; and means including hydraulic torque transmitting means of the kinetic reaction type operatively connected to said feeding means for causing material to be fed to said press at an automatically variable rate determined by the characteristics of the material under treatment.

2. In combination, a continuous screw press for expressing liquid from materials containing the same; continuously operating means for feeding said press; unitary means including an hydraulic torque transmitter of the kinetic reaction type for driving said press at a substantially constant rate, and said feeding means at a rate which varies with the characteristics of the material under treatment; and means for adjusting the torque transmitter to vary its range of action.

3. In combination, a main press of the continuous type for expressing liquid from materials containing the same; a continuous feeding press for expressing material and discharging it into the main press; a motor for driving the main press; means including an hydraulic torque transmitter of the kinetic reaction type interposed between said motor and said feeding press, for causing automatic regulation of the feeding press; and manual means for setting the range of operation of the automatic means.

4. In combination, a main continuous screw press having a horizontal barrel; a feeding press of the continuous screw type having a vertical barrel connected to discharge expressed material into the inlet end of the horizontal barrel;

a first motor for driving the main press directly; a second motor for driving the feeding means; and an hydraulic torque transmitter of the kinetic reaction type interposed between said second motor and said feeding press to permit variations in the rate of operation of the feeding press as the characteristics of the material under treatment vary.

5. In combination, a main continuous press having a horizontal barrel; a continuous feeding press having a vertical barrel connected to discharge expressed material into the inlet end of the horizontal barrel; a motor directly connected to said main press; hydraulic torque transmitting means of the kinetic reaction type, including two rotary vane elements operating in a fluid bath; means connecting one set of vane elements to the feeding press; and a motor for driving the other set of vane elements.

6. In combination, a main continuous screw press having a horizontal barrel; a feeding press also of the continuous screw type having a vertical barrel connected to discharge expressed material into the inlet end of the horizontal barrel; a motor; a hollow casing having vanes carried thereon; means for driving said casing from said motor; a vane element rotatably mounted in said casing and operatively connected to the movable element of the feeding press; a fluid in said casing for impositively transmitting the drive from said casing to said vane element; and means for adjusting said vane element with respect to the vanes on said casing to vary the range of response of said vane element and the movable element of the feeding press.

7. In combination, a main press of the continuous type for expressing liquid from materials containing the same; a continuous feeding press for expressing the material and discharging it into the main press; a driving connection for the main press; a driving connection for the feeding press, said latter driving connection including an hydraulic transmitter of the kinetic reaction type and adapted to modify the rate of operation of the feeding press in response to resistance of the material being pressed; driving means to operate said presses through said driving connections; and means for adjusting said hydraulic transmitter to vary the range of its transmitted driving torque whereby the range of automatic regulation afforded by said transmitter is adapted to the resistance characteristics of different materials.

RAYMOND T. ANDERSON.
